(57) **CLAIM**

The ornamental design for a cable spacer, as shown and described.

DESCRIPTION

FIG. 1 is a top, back perspective view of the cable spacer showing my new design;

FIG. 2 is a top, back perspective view of the cable spacer shown in an environment of use; and,

FIG. 3 is a top, front perspective view of the cable spacer. The broken lines in the drawings depict environmental subject matter only and form no part of the claimed design.
